UNITED STATES PATENT OFFICE.

CHARLES A. BARKER, OF DAYTON, OHIO, ASSIGNOR TO THE CRAIG-
REYNOLDS FOUNDRY COMPANY, OF SAME PLACE.

DESIGN FOR A FURNACE-FRONT.

SPECIFICATION forming part of Design No. 23,430, dated July 3, 1894.

Application filed May 24, 1894. Serial No. 512,391. Term of patent 7 years.

To all whom it may concern:

Be it known that I, CHARLES A. BARKER, a citizen of the United States, residing at Dayton, in the county of Montgomery and State of Ohio, have invented and produced a new and original Design for a Furnace-Front; and I do declare the following to be a full, clear, and exact description of the same, reference being had to the accompanying drawings, ⁵ forming a part thereof.

The design is for the front of a heating furnace, as shown in the drawings hereto annexed, in which—

Figure 1 is a front view of the furnace front. ¹⁵ Fig. 2 is a side view showing the general contour.

The special features of my design are the upper ornamental panel, the ornamentation of the doors, and the frame or border ²⁰ ²⁵ rounding the furnace front.

The frame consists of horizontal and vertical panels (a) (b) (c); the centers of these panels are decorated with medallions consisting of a rosette with ornamental figures above and below. On the two extremities of the ²⁵ panels (b) and (c) are scroll-like ornaments, and between said panels and the main front, there is a series of links forming chains (d) extending the entire length of the main front

of the furnace. The main front of said furnace consists specifically of an upper panel having a shield A in its center, and four sprays of inwardly curved and coved leaves, in relief, inclosing the sides of said shield. Below this panel is an intermediate panel, in ³⁰ which the feed door, and the air wheels are located; the ornamental features of this panel consist of four scroll-like designs occupying the four corners of the feed door, a twig (f) on either side of the feed door, and a fancy ³⁵ scroll (g) between the air wheels. The ornamentation of the lower panel, in which are located the clinker and ash-pit doors, consists of leaflets (h) located on the four corners of the ash-pit door, and scroll-like ornamentations (i) on the clinker, and draft doors, all of said ornamentations being in relief, and in harmony with the general design. ⁴⁰ ⁴⁵

I claim—

The design for a furnace front herein shown ⁵⁰ and described.

In testimony whereof I affix my signature in presence of two witnesses.

CHAS. A. BARKER.
